WINDOW STAGE

Filed Aug. 21, 1929

UNITED STATES PATENT OFFICE

LANNIS E. THRASHER, OF HAINES, FLORIDA

WINDOW STAGE

Application filed August 21, 1929. Serial No. 387,457.

My invention relates to improvements in window stages, more particularly to stages to which it is desired to hoist materials for use by the workmen on said stages and it 5 consists in the combination, constructions and arrangements herein described and claimed.

An object of my invention is to provide a window stage so constructed that it may 10 be secured to windows surrounded by walls of varying thickness.

A further object of my invention is to provide a window stage adapted for the hitching of the hoist thereto for the raising 15 of materials or other purposes for which my hitching ring might be used.

A further object of my invention is to provide a device of the type described which is simple in construction, has few parts and 20 is not likely to get out of order easily.

Other objects and advantages will appear in the following specification, and the novel features of the invention will be particularly pointed out in the appended claims.

25 My invention is illustrated in the accompanying drawings forming part of this application in which:

Figure 1 is a front elevational view showing my device in operative position on a 30 window frame.

Figure 2 is a rear elevational view of my device.

Figure 3 is a plan view of my device as seen from below in Figure 1.

35 Figure 4 is an end view of the invention showing the deck supporting means in operative position.

Figure 5 is a sectional view on the line 5—5 of Figure 1 with certain parts omitted.

40 Figure 6 is a perspective detail view of a portion of the device.

In carrying out my invention, I make use of a flat deck or platform 1 which may be made of wood or any other suitable material 45 mounted on a frame 2 constructed of angle iron or other suitable material. The platform 1 is secured to the frame 2 by suitable clamping means comprising the clamping plate 1a adapted to be clamped to the frame 2 by suitable clamping means such as the

bolt and nut shown at 1b as more clearly appears in Figures 3 and 6. The blocks 1c which are engaged with the frame 2 restrain the platform 1 against lateral sliding movement relative to the frame. 55

Fastened to this frame and extending downwardly therefrom are the brace arms 3 which support the frame against the wall below the window by means of the supporting blocks 4 secured thereto by fastening means 5. The arms 3 are secured to the frame 2 by the brace rods 6 fastened to the brace arms 3 by suitable means shown at 7. These rods 6 are connected to the frame 2 by the hook portion 6a engaging the apertures 2a in said frame. 60

The frame 2 has two laterally extending arms 8 projecting therefrom at right angles to the brace arms 3. These supporting arms 8 are provided with the pivot members 9 upon which are mounted the guard arms 10 providing the notches 11 and 12 for engagement with the supporting rod 13 and the latch means 14 respectively. The series of 70 notches 11 of each of the members 10 are in alignment with the series of notches on the other member 10 thereby providing suitable means for mounting the supporting rod on said arms 8. This supporting rod 13 is provided near its adjacent ends with the 75 pivotally mounted blocks 13a provided with felt or other similar friction surface for engagement with the walls surrounding the window. This prevents the supporting rod from sliding relative to said walls when said blocks are brought into engagement therewith. The latch 14 is provided with a compression spring 15 which normally urges said latch into engagement with the notch 12 thereby securing the member 10 in fixed position, thus maintaining the supporting rod 13 in fixed position in one of the pairs of notches relative to said arm and the wall. 80

For the purpose of hoisting material to platforms or of securing matter to said platform or for other purposes, I provide a hitching ring 16 suspended from the frame 2, by supporting rods 17 provided with retention hooks 17a for securing said rods 85

detachably to the frame 2. It will readily be seen that the hitching ring 16 provides a suitable means for fastening the hoisting apparatus containers for material or the like.

5 From the foregoing description of the various parts of the device, the operation thereof may be readily understood. This window stage, as previously stated, is designed for mounting on window frames surrounded by

10 walls of varying thickness. To accommodate this stage to such walls, it is merely necessary to compress the latch springs under the deck thereby releasing the guard arms 10 and thus permitting the supporting rod 13

15 to be inserted in any of the notches 11 of said guard arms 10 for accommodation of the particular wall to which the device is being fitted. The deck is then securely supported in fixed position by the block members 4 engaging the vertical exterior wall below the window and the blocks 13a engaging the interior walls beside the window. The device can readily be detached from the window frame by merely pressing the

20 latches 14, raising the guards 10 and taking from operative position the supporting rod 13 whereby the whole device is readily removable from the window. The hitching ring, of course, is readily attached or detached by means of the retention hooks at the will of the workmen using the window stage.

I claim:

1. A frame for supporting the deck of a window stage comprising supporting arms adapted to extend from said frame through the aperture of a window, a supporting bar adapted for engagement with the interior of the walls surrounding the aperture of

40 said window and means for adjustably securing said supporting bar to said supporting arms, consisting of slotted arms pivoted on said supporting arms and latches on said frame for securing said slotted arms in

45 position.

2. In a supporting frame for the deck of a window stage, supporting arms adapted to extend through the aperture of a window frame, adjustable means for fixing said supporting arms relatively to said window frame comprising guard arms pivotally mounted on said supporting arms and having a series of spaced alined notches, latches on the frame for securing said guard arms against pivotal movement, and a bar adapted to be placed in said spaced alined notches and adapted for engagement with the interior of the walls surrounding said window frame whereby said frame is adapted to be supported from window frames surrounded by walls of varying thickness.

3. A frame for supporting the deck of a window stage comprising downwardly projecting arms having friction surfaces for engagement with the wall below the window,

supporting arms adapted to project through the aperture of the window, a bar mounted on said supporting arms and having friction surfaces adjacent the outer extremities thereof for engagement with the inner wall and the window frame to prevent said bar from sliding, bars pivotally mounted on said supporting arms and having notches for engaging said bar, and spring pressed latches mounted on said frame for securing said notched bars in closed position.

LANNIS E. THRASHER.
